CORNELIUS J. KELLY, OF TAUNTON, MASSACHUSETTS, ASSIGNOR TO HOPEDALE MANUFACTURING COMPANY, OF MILFORD, MASSACHUSETTS, A CORPORATION OF MASSACHUSETTS.

FILLING-FEELER MECHANISM FOR LOOMS.

Application filed July 19, 1922. Serial No. 575,980.

To all whom it may concern:

Be it known that I, CORNELIUS J. KELLY, a citizen of the United States, residing at Taunton, in the county of Bristol and State 5 of Massachusetts, have invented certain new and useful Improvements in Filling-Feeler Mechanism for Looms; and I do hereby declare the following to be a full, clear, and exact description of the invention such as 10 will enable others skilled in the art to which it appertains to make and use the same.

The present invention relates to an improvement in filling feeler mechanism for looms.

15 One object of the present invention is to produce a filling feeler mechanism having a controller which, instead of striking the shuttle spring, strikes the shuttle, thereby eliminating variations in operation due to 20 differing positions of the shuttle springs.

To the accomplishment of this object, and such others as shall hereinafter appear, the present invention consists in the filling feeler mechanism hereinafter described and particularly pointed out in the claims.

In the accompanying drawing illustrating the preferred form of the invention, Figure 1 is a plan of a portion of the left hand end of a loom showing the application 30 of the improved filling feeler mechanism thereto; Fig. 2 is a view in side elevation of the parts shown in Fig. 1; Fig. 3 is a similar view with the parts in a different position and showing the cooperation of the feeler 35 with the bobbin; and Fig. 4 is a transverse sectional elevation of the filling feeler mechanism taken at the point where the pivot post is located.

The loom to which the improved filling 40 feeler mechanism is applied may be of any usual or preferred construction and may be either a plain loom or an automatic loom. The loom illustrated in the drawings is of the automatic weft replenishing type and 45 comprises a lay 9, provided in the usual manner with a shuttle box 12, in which the shuttle 13 comes to rest when properly boxed in position to permit the filling feeler mechanism to determine the extent to which the 50 filling on the bobbin has been exhausted. A longitudinal slot 14 is cut in the front wall of the shuttle to permit the filling feeler operation. A rock shaft 15 which is jour-

naled in suitable bearings at the front side of the breast beam extends across the front 55 of the breast beam and is operatively connected at the other end of the loom with the weft replenishing mechanism. Secured to the rock shaft 15 and projecting upwardly therefrom is an arm 16 to the upper end of 60 which is pivoted a rock shaft actuator 18. The rock shaft actuator 18, the arm 16 and the rock shaft constitute what is herein-after called the filling supply controlling means and they perform their function when 65 the filling in the active shuttle has been exhausted to a predetermined extent—that is to say, when there is critical exhaustion of the filling—to initiate the operation of the weft replenishing mechanism, and thereby 70 cause the insertion of a fresh supply of filling in the shuttle. The parts above enumerated, their actuating mechanism and their mode of operation, together with other parts necessary to a disclosure of the present 75 invention, are of the usual construction and well-known to those skilled in the art.

The improved filling feeler mechanism operates to determine the amount of filling on the active shuttle and upon critical exhaustion of filling to set in operation the supply controlling means. The filling feeler mechanism comprises a filling feeler generally indicated by the reference character 19, a controller 20 and a latch lever 21. The 80 filling feeler consists of a feeler lever 22 and a filling engaging member 23 having upon its rearmost extremity filling engaging teeth. The filling engaging member 23 is slidably mounted in two ears 26, 27, 85 90 projecting upwardly from the rearward part of the feeler lever. The filling engaging member is yieldingly pressed toward the bobbin 28 by a light tension spring 29 encircling the shank 30 formed on the 95 forward end of the member. One end of the spring engages a shoulder formed between the member and the shank and the other end of the spring engages the ear 27. The feeler lever 22 is pivotally mounted 100 on the vertical pivot pin 32 which is adjustably secured in the controller slide 20. The slide is provided with a slot shown in dotted lines at 33 in Figs. 2 and 3, and the pivot pin 32 may be moved longitudinally of the 105 slide in the slot and secured in adjusted

position therein. A washer 35 encircles the pivot pin and on the washer rests the feeler lever 22. A bearing sleeve 37 embraces the pivot pin and extends from the washer 35 at the bottom to the washer 39 at the top. By loosening the nut 41, the pivot pin may be moved in the slot as above described and then by tightening such nut the pin may be clamped in place by the exertion of pressure by the nut on the sleeve 37. The feeler lever 22 is secured to a hub 43 which fits over and is adapted to turn on the sleeve 37. The feeler lever has connected to it a laterally extended shoulder 45. Means are provided to engage this shoulder and prevent the feeler from turning at all times except when the controller, by means to be described, permits. A link 47 connects the forward end 20 of the feeler lever 22 with the latch lever 21. The latch lever is pivoted at 49 on the rock shaft actuator 18 and a spring 51 tends to turn the latch lever in a direction to cause the link to pull upon the feeler lever 22 and move its rearward end to the left so as thereby to move the filling feeler longitudinally along the surface of the bobbin. The rear end of the latch lever 21 is notched at 53 and when swung to the left, is adapted to be engaged by the weft hammer 25. The controller 20 is slidingly mounted in the bracket 61 secured to the left hand end of the knock-off bracket. The front end of the controller 20 is provided 35 with a lock lever support 63 which extends laterally and rearwardly as shown in Fig. 1 and has pivotally supported to its rear end the lock lever 65. This lock lever is a bell crank lever pivoted at 67 to the support 63 and its upper arm 69 when in normal position, as shown in Fig. 2, engages the shoulder 45 of the feeler lever. The lower arm 71 of the lock lever 65 is connected by means of an adjustable link 73 40 with the bracket 61 by the pin 75. One of the two members of this link 73 is slotted, as shown, and the bolt 77 unites the two members at the desired adjusted length. The construction is such that as the controller moves forwardly, it carries the pivot 45 of the lock lever with it and the lock lever is thereby tipped so that its upper arm 69 is removed from in front of the shoulder 45 of the feeler so that the latter may turn 50 upon its pivot in the event that the filling has been exhausted to such an extent as to permit it.

The controller slide 20 has a downwardly projecting lug 81 which extends into the slot 83 in the bracket 61. A second lug 85 extends downward from the controller slide 20 at the forward end thereof, and a rod 87 passes through the two lugs 81 and 85 and screws into the bracket at 89. 60 The lug 81 reciprocates in the slot 83, and

a spring 91 encircles the rod 87 and by abutting a portion of the bracket 61 normally holds the controller slide in rearward position.

The mode of operation of the device is as follows: In normal operation with each forward beat of the lay, when the shuttle is boxed on this side of the loom, the controller is moved forward after the feeler lever has had opportunity to engage the filling, and it thereby tilts the lock lever 65 and frees the feeler lever 22. Until the filling is exhausted to the critical extent, it prevents the swinging of the feeler lever under the influence of the latch spring 51 which, through the latch 21 and the link 47, can turn the feeler end to the left. But when critical exhaustion is reached, the filling on the bobbin no longer prevents the swinging of the feeler, and the latch lever 80 is presented to the weft hammer, and thereupon filling replenishment is secured by pushing forward the latch lever and operating the filling controlling mechanism.

Viewed in its broader aspects, the invention contemplates a filling feeler adapted for use to knock off the loom as well as to control filling replenishment, but the important use of the invention is, of course, in securing filling replenishment.

Having thus described the invention, what is claimed is:

1. A loom having, in combination, a lay, a shuttle, a filling carrier, and filling feeler mechanism comprising a controller mounted to move toward and from the lay, a feeler pivotally mounted on the controller, the controller having its rear end adapted to be engaged by the shuttle, and the feeler being mounted above the controller so that the feeler engages the yarn at a point on the bobbin immediately in the rear of the point where the controller engages the shuttle.

2. A loom having, in combination, a lay, a shuttle, a filling carrier, and filling feeler mechanism comprising a bracket, a controller slide mounted to move forward and back in the bracket, and having its rear end adapted to engage the shuttle, a filling feeler pivotally mounted on the controller, a lock lever connected to the controller and operated thereby to release the feeler when the controller is struck by the shuttle.

3. A loom having, in combination, a lay, a shuttle, a filling carrier, and filling feeler mechanism comprising a support, a controller slidingly mounted in the support having its rear end adapted to be struck by the shuttle, a feeler lever pivotally mounted on the controller provided with a shoulder, a lock lever also mounted on the controller, and means for connecting the lock lever with the support so that when the controller is moved forwardly the lock lever is moved forwardly and is removed from in front of

the shoulder of the feeler lever, and means for operating the feeler on critical exhaustion of the filling.

4. A loom having, in combination, a lay, 5 a shuttle, a filling carrier, and filling feeler mechanism comprising a support, a controller slidingly mounted in the support having its rearward end adapted to engage the shuttle, a feeler lever pivotally mounted on 10 the controller, having its filling feeler end extending rearwardly beyond the end of the controller and adapted to engage the filling on the filling carrier, a lock lever pivotally mounted on the controller, connections be- 15 tween the lock lever and the support for swinging the lock lever when the controller is moved forwardly, a portion of the lock lever being adapted to engage a portion of the feeler lever to prevent such feeling 20 movements of the feeler lever at all times except when the controller is moved forward by engagement with the shuttle.
5. Filling feeler mechanism for looms, comprising a support, a controller slidingly 25 mounted on the support, a spring normally holding the controller in its rearward po-

sition, a feeler lever, a pivot pin for the feeler lever secured to the controller, the latter being provided with a slot permitting the pivot pin to be secured to the controller 30 at different positions, a bell crank lock lever pivoted near its angle to the controller, having an upper arm and a lower arm, the lower arm being connected by a link to the support, and the upper arm being adapted 35 to engage a portion of the feeler lever to prevent the turning of the latter in feeling movement except when the controller is in forward position.

6. A loom having, in combination, a lay, 40 a shuttle, a filling carrier, and filling feeler mechanism comprising a support, a controller slidingly mounted on the support and adapted to engage a lay part, and a laterally movable feeler mounted on the controller, the feeler and the controller being 45 adapted for relative forward and rearward movement with respect to each other.

7. A loom as described in claim 6 in which the feeler is normally supported vertically 50 above the controller.

CORNELIUS J. KELLY.
